Patented Dec. 6, 1927.

Des. 74,039

UNITED STATES PATENT OFFICE.

EDWARD M. WARE, OF HADDONFIELD, NEW JERSEY.

DESIGN FOR A BEDCLOTHES HOLDER.

Application filed June 5, 1924. Serial No. 9,805. Term of patent 7 years.

To all whom it may concern:

Be it known that I, EDWARD M. WARE, a citizen of the United States, residing in Haddonfield, Camden County, New Jersey, have invented a new, original, and ornamental Design for a Bedclothes Holder, of which the following is a specification, reference being had to the accompanying drawing, forming part thereof, in which the figure is a view in perspective of the bedclothes holder.

I claim:

The ornamental design for a bedclothes holder, as shown.

EDWARD M. WARE.
